UNITED STATES PATENT OFFICE.

JOHN TWARDUS, OF HARTFORD, CONNECTICUT.

DIRIGIBLE BALLOON.

Application filed June 10, 1920. Serial No. 387,944.

To all whom it may concern:

Be it known that I, JOHN TWARDUS, a citizen of the United States, and a resident of Hartford, in the county of Hartford and 5 State of Connecticut, have invented new and Improved Dirigible Balloons, of which the following is a specification.

My invention relates to flying structures of various types, one feature of the invention embodying an apparatus comprising an 10 inflatable bag with propelling and steering mechanism therefor, and an object of my invention, among others, is to provide a bag by the use of which the expense attending 15 its inflation may be minimized; a further object of the invention is to provide a bag having means to regulate pressure therein; and a further object of the invention is to provide a bag with means for maintaining 20 the element of safety at a high degree.

One form of device embodying my invention and in the construction and use of which the objects herein set out, as well as others, may be attained, is illustrated in the 25 accompanying drawings, in which—

Figure 1 is a view in side elevation of a flying structure embodying my invention.

Figure 2 is a bottom view of the same.

Figure 3 is a view in cross section through 30 the structure, illustrating the operation of the contraction means, the section of the bag being illustrated by a heavy black line.

Figure 4 is a view in horizontal section through the rear part of the bag illustrating 35 the arrangement of the means for contracting it, the cross sectional dimension of said bag being illustrated by a heavy black line.

Figure 5 is a detail face view, scale enlarged, illustrating the manner of attaching 40 the distributors to the contraction web. Figure 5^a is a sectional view showing the attachment of the contraction web to the bag.

Figure 6 is a detail view, scale enlarged, 45 illustrating the connection between the distributors and the contractors.

Figure 7 is a detail view, scale still further enlarged, in longitudinal section through a contractor tube, the section of 50 which is denoted by a heavy black line. This figure also shows a side view of a portion of one of the upper cross pieces of the hull and a cross section of the same and with a contractor sheave secured to its under side.

Figure 8 is a view in cross section, scale

still further enlarged, through a contractor tube on a plane passing through one of the joints.

Figure 9 is a detail view on the same scale 60 as Figure 8 in longitudinal section through a portion of a contractor tube and illustrating the attachment of the membrane thereto and to the gas bag.

Figure 10 is a rear view on enlarged scale 65 of one of the pontoons.

Figure 11 is a detail view in lengthwise section through a part of the pontoon illustrating the function of one of the entrance doors.

Figure 12 is a detail view in section illustrating the construction of the pontoon at 70 the point of entrance thereto, this view being enlarged over Figures 10 and 11.

Figure 13 is a detail view, scale still further enlarged, illustrating the packing at 75 the door opening.

Figure 14 is a detail view, scale enlarged, 80 illustrating the connection of the membrane with the elevating planes.

Figure 15 is a detail view, scale still further enlarged, in section through the spring cases of said connection.

Figure 16 is a detail view, scale enlarged, 85 illustrating the construction of the frames comprised in the hull and the attachment of the struts thereto.

Figure 17 is a detail view, scale enlarged, illustrating the construction of the wheels.

I have filed concurrently herewith an application for patent on flying structure, the 90 general arrangement of which is like that illustrated and described herein and I, therefore, confine the description herein mainly to features not shown and described 95 in the copending application and do not go into detail as to the general construction.

While the invention of this application is illustrated in connection with a flying structure embodying an inflatable bag that 100 is, however, intended to only partially float the structure, yet many of the features will be found equally applicable to flying structures of other and various types.

In the inflation of balloons the extreme 105 danger from the use of hydrogen gas, owing to its highly inflammable qualities, is well known and as is further well known danger from fire may be reduced to a minimum by the use of helium. The scarcity of this 110 medium is so great as to make its use prohibitive in many cases. I have provided in

the structure herein illustrated and described means whereby helium may be employed in the gas bag in a manner to greatly reduce the danger from explosion, 5 above referred to, my improved bag being so constructed that the helium may be employed in small quantities and so disposed as to provide a shield for the hydrogen gas which is used in larger quantities and thus 10 materially reduce the chances of the latter taking fire.

Such a structure is shown in the accompanying drawings in which the numeral 20 indicates my improved gas bag that is constructed of any suitable and desired material and that is preferably round in shape in cross section as to all except the extreme lower portion. The sides of this lower portion are preferably formed on curves intersecting the upper portion at an angle, and the bottom of this lower portion is formed on a curve of larger diameter as compared with the rest of the bag so that the bottom is quite flat and as shown in Figure 3 of 25 the drawings. The angle formed at the meeting points between the upper and lower portions of the bag extends completely around it in a lengthwise direction and a membrane 21 is secured to the inside of the 30 bag underlying of such angle and extends completely across the bag from end to end, thus dividing the bag into two chambers, a hydrogen chamber 22 at the top and a helium chamber 23 at the bottom thereof, the latter 35 chamber, as will be seen from Figure 3 of the drawings having the form of a trapezium, and smaller in cross sectional area as compared with the hydrogen chamber. Any well known means for introducing gas to 40 these chambers may be employed.

The bag as a whole is pointed at its front end and is curved downwardly on top at its rear end, the bottom being substantially straight lengthwise of the bag from the rear 45 to a point near the front end from which point it curves upwardly, as shown in Figure 1 of the drawings.

In order to regulate the pressure of the 50 hydrogen gas in the chamber 22 I provide means for reducing the size of such chamber at its upper part, such means comprising narrow contraction webs 24 secured to and projecting from the inside of the bag on correspondingly opposite sides thereof and 55 preferably above a diametrical plane extending horizontally across the bag, the terms, horizontally, vertically &c., being employed herein with the understanding that the bag is in the position normally 60 assumed when inflated, and as shown in Figure 1 and 3 of the drawings. The edges of these contraction webs are preferably engraved in the shape of small parabola curves disposed on the catenary principle. 65 Secondary distributors 25, in the form of

cords, extend through pockets formed in the edges of the webs 24, these distributors passing out of said pockets at each of the points 26 where they are joined into single strands comprising secondary connectors 27 70 extending to and joined with main distributors 28 formed in the shape of larger parabola and catenary curves extending lengthwise of the bag. The main distributors 29 at the stern and forward parts of the bag 75 are shorter than the main distributors at the midsections 30, main connectors 32 extending from points 31 between adjoining main distributors on one web to corresponding points on the opposite web. These main 80 connectors 32 are secured in loops comprising a knot formed by joining two adjacent main distributors 28 with a secondary connector 27 (see Figure 6). Contractors are connected at the center of each of the main 85 connectors 32, these contractors and the main distributors being shown by dotted lines in Figures 1 and 2. Each of the contractors passes downwardly through a flexible contractor tube 35 closed at its 90 upper end and secured thereto and to said contractor to prevent access of gas into the tube. Each of said tubes passes through the membrane 21 and is attached at its lower end to the bottom of the bag, being 95 connected to said parts in a manner to prevent access within the tube of gas from within the bag.

Each tube is preferably made from vulcanized rubber fabric comprising a plurality 100 of lengthwise extending strips 36, three such strips being shown herein (see Figure 8). These several strips are joined at their edges and they, and consequently the tube as a whole, are disposed in a plurality of concaved forms extending lengthwise of the tube (see Figure 7 of the drawings). Stiffening rings 37, of any suitable material, are secured to each tube at the angles formed by the intersection of said concave 110 surfaces, and consequently at the largest diameter of the tube 35, these rings being secured to the tube and inclosed by suitable straps cemented or otherwise secured to the outer surfaces of the tubes. 115

A mid-contractor 34 is illustrated in Figures 7 and 9 and the general arrangement of all of these contractors will be readily understood from this showing, it being stated that said contractors are passed 120 through the bottom of the bag 20 and around a contractor sheave 39 rotatably mounted in brackets secured to the under side of upper cross pieces 38 of the hull to hereinafter be described. After passing the sheave the 125 mid-contractor 34 and a stern-contractor 33 pass forwardly along the hull each to a separate drum or cylinder to which they are secured and by means of which they may be drawn to pull opposite sides of the gas 130

bag at the top inwardly into a position as indicated in dotted outline in Figure 3. The mid-contractor 34 is wound on a drum of larger diameter and the stern contractor 5 on a drum of smaller diameter, both drums rotating on the same axis and operated by a device similar to that shown in my copending application hereinbefore referred to. It will also be understood that the contractors at the forward part of the structure are arranged in the same manner except that they pass rearwardly to a point near the lengthwise center of the hull, whereas those at the stern part of the structure 10 and above described pass forwardly to a point near the lengthwise center of the hull. All four drums rotating on two axes are mounted in one frame located on the upper cross pieces in the center of the passenger-car.

From this construction it will be seen that when the contractors are pulled downwardly each tube will fold between the rings 37, thus decreasing in length to accommodate 25 itself to such movement of the contractor, and the free passage of the contractor through the membrane 21 permitted by such rings avoids any transmission of force from said contractor to said membrane, and the 30 latter is free to be acted upon by the pressures within the chambers 22 and 23. As the contractors are pulled downwardly and the sides of the bag are thereby pulled inwardly the size of the chamber 22 is decreased, thereby increasing the pressure of 35 the gas therein, and this pressure will be transmitted to the membrane 21 and as the chamber 23 is very shallow as compared with its horizontal dimensions the pressure 40 in the chamber 22 will be readily communicated through the membrane to the chamber 23.

The hull is the same as embodied in my copending application hereinbefore referred 45 to and filed June 10, 1920, S. No. 387,943 upon which issued patent to me dated May 6, 1924, No. 1,493,298, and comprises, generally speaking, longerons 40 of a length substantially equal to that of the bag, bottom cross 50 pieces 41, the top cross pieces hereinbefore referred to and uprights 42, all of said parts being cross and otherwise braced in any suitable manner, and the portion comprising the passenger car also having a bracing structure 43 including uprights and diagonals 55 arranged as may be desired. Struts 44 are pivotally secured at the top of the hull and extend outwardly therefrom, and they are preferably connected to the top longerons 60 at the junction of the upper cross pieces thereto. The outer ends of these struts are secured to the bag substantially at the angular portion thereof comprising the outer edges of the bottom and by means of loops 65 45 formed in yielding tension supports 46

securely fastened in slots within the outer ends of the struts 44, said loops passing through and over bends in primary supports 47 arranged in small parabola curves, as shown in Figure 1 of the drawings. Wire 70 braces 48, secured to the loops 45, extend diagonally downward to the bottom longerons to which they are rigidly secured preferably at the angles of intersection therewith of the bottom cross pieces (see 75 Figure 16).

Two sets of rigid elevating planes are secured to the hull, projecting laterally therefrom, one set being located substantially at the forward end of the midsection of the structure and the other at the rear end thereof, each of these sets of planes including a lower plane 49 and an intermediate plane 50 secured respectively to the bottom and top longerons of the hull, and a top plane 80 51 located above the intermediate plane, said planes being connected and supported by interplane struts and the whole being wire cross braced in any suitable manner. The nacelle struts for motors 53 are located 85 between the interplane struts 52 and at opposite sides of the structure, said motors being supported between the lower and intermediate planes with their propellers 54 in advance of the front edges of said planes. 90 Movable elevating planes 55 are pivotally attached in pairs to the spars at the rear edges of the bottom and intermediate planes, each member of each pair being located one 95 above the other directly back of the propellers.

Rudders 56 are mounted in pairs, one pair forward of the forward set of elevating planes and the other pair back of the rearward set of elevating planes, said rudders 100 being operated in any suitable manner, as for instance in the manner set out in my copending application hereinbefore mentioned, the structure comprising the hull, its supports and braces and the rigid elevating planes, together with the driving mechanism herein described also being more specifically set out in said copending application.

I provide means to hold the gas bag rigid 115 at its lower part by connecting it to the rigid planes hereinbefore described, in the structure herein shown the membrane 21 extending through the seam 57, connecting the upper and lower parts of said bag, said seam 120 being so formed as to tightly and rigidly secure the membrane 21 to the side parts of the bag. (See Figure 9.) The extended part 125 of the membrane forms flat stays 58 which may be reinforced at their edges as by means of cords sewed into a loop in a manner that will be readily understood. These stays are curved as to their edges, as shown in Figure 2 of the drawings, and they are secured to the upper planes 51 each by a yielding means 130

comprising a spring 59 located in a case 60 secured to the spars of the frame, as clearly shown in Figures 14 and 15 of the drawings. A rod 61 secured to one end of the spring 5 passes therethrough and has a ring in its outer end to which the points 62 of the stays are secured in any suitable manner. This resilient connection of the membrane to the stays allows the former to yield to pressure 10 inside the bag and to assume a concaved or convex form as may be required by reason of the expanding or contracting gas in the lower compartment.

Two sections of the hull that actually and 15 directly support two sets of rigid wings at opposite ends of a long passenger car are extended downwardly in the form of two small cabins 63. Both of these extensions are constructed as integral, inseparable parts 20 of the hull by means of long vertical members and diagonal braces that are mutual parts of both the hull and the extension structures, as shown in Figures 1, 2 and 10 of the drawing. This structure possesses decided advantages for aeronautical structures, 25 as the former embodies suspended or detachable cabins for dirigibles that are of extreme strength and stiffness and also of minimum weight, which advantages are not 30 present in structures heretofore made. Both of said extensions are of substantially the same shape and dimensions and serve the purpose of pilot houses, to provide for unobstructed view in all directions, as well as a 35 base for strengthening motor bearings, and wings by diagonal braces connecting the bottom of each extension with points on the wings that actually support said motor, and as two points for support of the whole long 40 structure to keep it above the ground or in lengthwise balance when supported on the water, both of said extensions being so constructed as to their lower part that they will 45 float. They are preferably rounded on the front sides and the bottoms are also rounded 50 upwardly at the front. Entrance to the passenger car is by means of a door 64 in the back of each cabin and by a ladder 65 extending upwardly from each cabin through 55 an opening in the bottom of the car. The door is hinged at its lower edge and step bars 66 are secured to the cabin both inside and out underneath the door. A step 67 is 60 also secured to the inside of the door and this will be placed in position for use when the door is swung downwardly. When 65 alighting on water should it be smooth the door may be opened for entrance to or departure from the car. When thus opened 60 the door will rest on the step 66 and the step 67 will be made use of. Should the water be rough the door will remain closed, and entrance will be had through the opening over the door. A packing strip 68 is 65 attached to the inside of the door on both

sides of the opening into the cabin and on the bottom to make the joint watertight where the door rests against the pontoon.

Wheels 69 are placed in the bottom of the cabin, and these wheels may be arranged in any suitable manner to serve for traction purposes. These wheels each consist of an axle 70 having plates 71 secured near opposite ends thereof, the wire spokes being secured to these plates. Clamp plates 72 are 75 secured to the plates 71 to clamp a water-proof fabric 73 in place, this fabric having an opening at its center, the edge of which is clamped between the plates 71 and 72 and the other edge of said fabric being secured to the rubber tire 74 close to the rim. Water is thus prevented from entering within in the wheel and the parts therein are thus protected.

I claim—

1. A flying structure comprising an inflatable bag, a single partition extending across the bag and secured at its opposite edges to opposite sides of the bag above the bottom and to the inner surface thereof 90 dividing said bag into upper and lower compartments, said partition being of a size to cause it to be taut when the bag is inflated, a non-inflammable gas possessing lifting power confined within the lower compartment, an inflammable gas confined within the upper compartment, and means secured to the underside of the bag for support of weight thereby.

2. A flying structure comprising an inflatable bag, contraction webs attached to and projecting from the inside of the bag on opposite sides of the upper part thereof, and extending lengthwise thereof, connectors attached to the edges of said webs at different points lengthwise thereof and extending across the upper part of the bag, contactors attached to said connectors and extending through the bottom of the bag, and means secured to the under side of the 110 bag for the support of weight thereby.

3. A flying structure comprising an elongated inflatable bag, webs attached to the inside of the bag and extending horizontally therealong on opposite sides of the upper 115 part thereof and projecting inwardly, the edges of said webs being engrailed in the form of small parabola curves, connectors extending horizontally between the projecting points of opposite webs, contractors secured to said connectors and extending through the bottom of the bag, and means secured to the under side of the bag for the support of weight thereby.

4. A flying structure comprising a 125 streamline shaped inflatable bag, webs attached to the inside of the bag on opposite sides of the upper part thereof and extending laterally inwardly, distributors disposed laterally in the form of large parabola 130

curves, means connecting said distributors with the edges of said webs, means for operating said distributors to move said webs with the sides of the the top of the bag 5 inwardly to decrease the space therein, and means secured to the under side of the bag for the support of weight thereby.

5. A flying structure comprising an inflatable bag, webs attached to the inside of the bag on opposite sides of the upper part thereof and projecting horizontally inward, distributors disposed substantially horizontal in the form of large parabola curves, means connecting said distributors and the edges of said webs, connectors extending between the points of said distributors on opposite sides of the bag, contractors secured to said connectors and extending through the bottom of the bag, and means 20 secured to the underside of the bag for the support of weight thereby.

6. A flying structure comprising a streamline-shaped, inflatable bag, webs with engrailed edges extending along opposite sides 25 of the bag, cords arranged in the form of small parabola curves joined at angles to each other and secured in said engrailed edges of the webs, distributors disposed on both sides of the bag in larger parabola 30 curves, connectors joining the points of the said cords with said distributors, connectors joining the points of said distributors on one side of the bag with the points of those on the other side of the bag, and means for 35 operating said connectors.

7. A flying structure comprising a streamline-shaped, inflatable bag, webs attached to the inside of the bag and extending uninterrupted along opposite sides of the 40 upper part thereof, cords in the form of small parabola curves each with its apex close to the gas bag engrailed in the edges of said webs, distributors disposed laterally on both sides of the bag in the form of large 45 parabola curves, each with its apex close to the gas bag, parallel, horizontally extending cords connecting said webs at its projecting points with said distributors, contractors attached to the points of said distributors and 50 extending through the bottom of the bag, means to move at will said contractors, distributors and webs together with opposite sides of the gas bag to decrease the space therein separately at the front and at the 55 rear to shift the gas from one of the bags to the other end thereof for lengthwise balancing of said structure, and means secured to the under side of the bag for the support of weight thereby.

60 8. A flying structure comprising an inflatable bag, a membrane extending across the bag and dividing it into an upper compartment and a comparatively shallow lower compartment, a rigid frame secured to opposite sides of the bag for the support of

weight thereby, and stays secured to the bag along the line of said membrane, said stays also being connected to the rigid frame to maintain said membrane in a taut condition.

9. A flying structure comprising an inflatable bag, a membrane extending across the bag to divide it into upper and lower compartments, a contractor secured to the inside of the upper part of the bag, an accordion tube secured to said membrane and 70 to the contractor at a distance from the bottom of the upper compartment, an accordion tube secured to said membrane and extending into the lower compartment, a connector secured to the inside of the top 75 of the bag and extending through said tubes and means secured to the under side of the bag for the support of weight thereby.

10. A flying structure comprising an inflatable bag, a membrane extending horizontally across the bag dividing it into upper and lower compartments, an accordion tube tightly secured at its end to the bottom of the bag and extending through 80 said membrane to which it is tightly secured, a contractor attached to the inside of the top of the bag and extending through said tube, and means secured to the under side of the bag for the support of weight 85 thereby.

11. A flying structure comprising an inflatable bag, a membrane extending across the bag through the sides thereof and secured thereto by a seam, means secured to 90 the bottom of the bag for the support of weight thereby, and means secured to the projecting part of said membrane for support of the bag.

12. A flying structure comprising an inflatable bag, a membrane extending across the lower part of the bag and through the sides thereof forming a seam extending completely therearound, a hull secured to the bottom of the bag, elevating planes supported by said hull, and means for attaching the projecting part of said membrane to said planes for the support of the bag.

13. A flying structure comprising an inflatable bag, a hull secured to the bottom of the bag, elevating planes rigidly supported by said hull and projecting laterally therefrom at different points along its length, supporting means in the forms of 115 webs secured to opposite sides of said bag and having their edges formed on parabola curves, and means connecting the parts of intersection of said curves with said elevating planes.

14. A flying structure comprising an inflatable bag, a membrane extending across the interior of the bag and secured to the sides thereof, forming a seam creating an angle in the outer surface of the bag extending 120 125

- lengthwise thereof, a frame supported by said bag, and stays extending along the line of said seam and secured to the bag thereat and to said frame.
15. A flying structure comprising an inflatable bag, a membrane extending across the lower portion of the bag and through the sides thereof forming a seam, extending completely therearound, the outer edges 10 of said membrane being formed on parabola curves, a hull secured to the under side of the bag, rigid elevating planes supported by said hull at the points of intersections of said parabola curves, and means for attaching the edges of said membrane to said rigid plane.
16. A flying structure comprising an inflatable bag, supporting means extending from opposite sides of the bag, a hull secured to the under side of the bag, elevating planes rigidly connected with said hull and projecting laterally therefrom at different points along its length, and means for 20 yieldingly connecting the edges of said supports to said elevating planes.
17. A flying structure comprising an inflatable bag, a membrane extending across the lower portion of the bag and through the sides thereof forming a seam extending 30 therearound, the projecting edges of said membrane being formed in parabola curves, a hull secured to the under side of the bag, elevating planes rigidly secured to said hull and projecting laterally there- 35 from opposite the termination of said parabola curves, and means for yieldingly connecting the edges of said membrane to said elevating planes at the termination of said curves.
- 40 18. A flying structure comprising an inflatable bag, a hull secured to the under side of the bag, a pilot house secured to the under side of said hull and comprised of a portion of the hull structure extended for 45 such purpose, the lower part of said house being watertight, steering mechanism in- cluding steering devices in said house, a door for entrance to said hull, a step projecting from said house to form a rest for said door, and means for rendering the opening closed by said door impervious to water.
19. A flying structure comprising a streamline shaped inflatable bag, a long 50 rectangularly shaped hull secured to the under side of said bag and extending lengthwise thereof, the median part of said hull extending at equal distances from the transverse center of gravity of said structure, two extensions projecting downwardly 55 from the hull under both ends thereof and in the form of small cabins having upright and diagonal members mutual with corresponding members in sections of the hull, both of said extensions being adapted 60 as pilot houses, and a wheel mounted on the bottom of each of said extensions.
20. A flying structure comprising a streamline shaped inflatable bag, a long 65 rectangularly shaped hull secured to the under side of said bag and extending lengthwise thereof, the median part of said hull at equal distances from the transverse center of gravity of said structure being adapted 70 as a passenger car, extensions in the form of small cabins projecting downwardly at each end of said passenger car, both of said extensions having uprights and diagonal members 75 mutually corresponding with similar members in the overlying section of the passenger car, means for access to said car through each of said extensions, the latter having upright door openings, doors to close the lower parts of said openings and seal them against inflow of water, a step bar 80 on the outside of each extension, a step bar mounted to correspond therewith on the inside of the extension below the door, and on said door, and a wheel mounted on the bottom of each of said extensions.

JOHN TWARDUS.
